US0D1106771S

(12) **United States Design Patent** (10) **Patent No.:** **US D1,106,771 S**
(45) **Date of Patent:** **** Dec. 23, 2025**

(54) **CUP HOLDER**

(71) Applicant: **Guangzhou Zhongtianxin Electronic Technology Co., Ltd**, Guangzhou (CN)

(72) Inventor: **Zhenghui Fu**, Guangzhou (CN)

(73) Assignee: **Guangzhou Zhongtianxin Electronic Technology Co., Ltd**, Guangzhou (CN)

(**) Term: **15 Years**

(21) Appl. No.: **29/917,534**

(22) Filed: **Nov. 20, 2023**

(51) LOC (15) Cl. **07-09**

(52) U.S. Cl.

USPC **D7/620**
